J. M. DODDRIDGE

GATE HINGE

Filed July 25, 1924

Patented May 12, 1925.

1,537,420

UNITED STATES PATENT OFFICE.

JAMES M. DODDRIDGE, OF MILTON, INDIANA.

GATE HINGE.

Application filed July 25, 1924. Serial No. 728,089.

To all whom it may concern:

Be it known that I, JAMES M. DODDRIDGE, a citizen of the United States, residing in the town of Milton, in the county of Wayne, 5 State of Indiana, have invented new and useful Construction for Gate Hinges, of which the following is a full, clear, and comprehensive specification and exposition, the same being such as will enable others to 10 make and install the same with exactitude.

The object of my present invention, broadly speaking, is to provide a hinge construction which is comparatively simple in character, strong and dependable in construction, adjustable either before or after 15 being installed, and which can be manufactured and sold at a comparatively low price.

More particularly stated, my object is to provide hinges intended more especially for 20 heavy gates and concrete posts, with means whereby they may be easily and permanently secured in operative position, and having means whereby they may be adjusted horizontally at various angles, such as forwardly 25 and backwardly, and to the right or the left, and whereby the gate may be alined or adjusted either when first being installed, or at any time thereafter without the removal of the gate from its post.

Other objects and particular advantages 30 of the invention will suggest themselves in the course of the following description, and that which is new will be correlated in the appended claims.

The preferred means for carrying out the 35 objects of my invention in a practical and mechanically efficient manner is shown in the accompanying drawings, in which—Figure 1 is an elevation showing both the upper and the lower hinge assemblies in position in connection with a post and a gate. Figure 2 is a left-hand face elevation of one 40 of the gate units of a hinge. Figure 3 is a right hand face elevation of one of the gate units of a hinge. Figure 4 is an inside view of a portion of one of post units of a hinge. Figure 5 is a detail view of one of the stubs of a post unit. Figure 6 is a cross section, as taken on the line 6—6 of Fig. 2. 45 And Figure 7 is an enlarged top plan view of the yoke 11.

Similar indices denote like parts throughout the several views.

In order that the construction, the operation, and the several advantages of my invention may be more fully understood and

appreciated, I will now take up a detailed description thereof, in which I will set forth the same as comprehensively as I may.

In the drawings letter A designates a concrete post which supports a gate. The gate comprises an upper rail B and a lower rail C, connected by a plurality of rods or pickets D, E, F and G.

As will be observed, the upper and the lower hinge units are identical with each other in all parts except that the lower hinge unit is turned end for end with relation to the upper, and the two hinge units of the gate are connected by the bar 1 which is common to both, therefore for convenience of description I will refer to the upper hinge unit, designating the parts by certain numerals, and will simply denote the corresponding parts of the lower hinge members by like numerals with exponents. Also I will refer to the parts of the gate hinge toward the post and to the parts of the post hinge toward the gate as inward, while to the parts to the right and the left of the line between the post and the gate will be referred to as outward.

The elongated plates 2, 2', each has a channel extending the full length thereof in the outer faces, which channel is of the same width and depth as is the thickness and width of the bar 1, that is to say, such as to receive said bar therein.

The ends of said bar 1 are rounded, and the end portions of said bar are turned outward at right angles to the bar, thereby forming the lips 3—3'. The end portions of said bar 1 is secured to the plates 2 and 2', in the channels thereof, by the respective bolts 4—5 and 4'—5', as indicated. Said bolts being disposed through slots in the plates whereby the plates may be adjusted on the bar.

Extending across through the centers of the plates 2, 2', are oblong apertures, as the aperture 6, shown in Fig. 3. The central portions of each edge of the plates have enlargements, 7—7 and 7'—7', which are concentric with the respective apertures 6.

Indices 8, 8', denote set-screws, which are threaded through the enlargements of said plates, and their points enter the respective apertures 6, the members of each pair being in direct alinement with each other, as shown in Fig. 3.

It is to be noticed that the bar 1 does not extend the full length of the channels in the

plates, but extends to near said enlargements. However a short section of the same size bar, as the bar 1, is located in the other end portions of said channels, as for instance the section H shown in Fig. 2, and they extend to near the other ends of said enlargements.

Indices 9—9' denote brackets, secured to its section of bar H and the plates 2—2', by the respective bolts 10, 10'. Indices 11, 11', denote yoke-shaped members, each comprising a vertical portion and two horizontal portions extending inward from the vertical portion. One horizontal portion of each yoke is connected with brackets 9, 9', with the inner end portion of the bar B, and C, therebetween, by bolts 12, 12', which pass through the apertures y. And the other horizontal portion of the yokes are connected to the lips, 3, 3', by the bolt 13, 13'.

Indices 14, 14', denote lips, formed integral with the yokes 11, 11', and in alignment with the horizontal portions of the yoke which are secured to the brackets 9, 9'. Said lips 14, 14', contact with the bars B and C, and there is a slot x formed across and through each lip 14, 14', to receive the bolts 15, 15', which connect said lips to said bars as shown. Said slot x and aperture y being shown in Fig. 7.

Indices 16, 16', denote the hinge stubs, each comprising a disc head and a stem with its outer portion threaded to receive thereon the nuts 17—17 and 17'—17'. The stems of said stubs are inserted through the respective slots 6, with their threaded portions inserted in apertures therefor formed through the vertical portions of the yokes, which ends are adapted to be locked by a pair of nuts 17—17, and 17'—17', which clamp upon the yoke as shown.

At the same time, said stubs are secured on the slots 6 by means of the set-screws 8—8 and 8'—8', as shown in Fig. 3.

By the above it will be seen that I now have the stub members of the hinges whereby they are adapted to be adjusted laterally or longitudinally thereof as desired.

The post units of the hinges each comprises a box-like construction comprising the two portions 27 and 28, 27'—28', which are identical with each other, each part having ears 19, with apertures through the ears whereby the two members may be secured together by screws or bolts to form the enclosures. Each member of the boxes has an outwardly projecting swell portion 20, forming inner shoulders and outer shoulders, as shown in Fig. 1.

Formed in the inner (left Fig. 1) ends of the boxes is a vertical slot 21, for the purpose hereinafter stated. Indices 22, 22', denote the post stubs, each having a disc-like head and a stem whose end portion is threaded as shown. The stubs 22, 22', are

identical with the stubs 16, 16', except that the faces of the heads or discs are formed at an angle with relation to each other in place of being parallel with each other, the purpose of which is that the boxes may be placed at an angle, as shown.

Each of said boxes contains a nut, 23 and 23' respectively, which is adapted to contact with the inner shoulders of said projections 20, and the threaded portions of the stubs 22, 22', are threaded into their respective nuts as shown. Each of the parts 17, 18, 17' and 18' carries a set-screw 24, which set-screws are threaded into said members of the boxes whereby their end portions may be run into the ends of the respective slots 21, and impinge the stems of the stubs 22, 22', and whereby said stubs may be adjusted vertically, and secured in their adjusted positions.

The post hinge-units are to be imbedded in the concrete of which the post A is formed, with the slotted end of the boxes projecting a short distance from the face of the post, such as to permit the set-screws 24 to be operated at any time. The angular positions of said boxes prevent moisture from accumulating therein or therearound, that is permitting water to drain therefrom.

When the various parts are assembled as set forth, then the gate may be lifted up, bringing the discs of the stubs 16, 16' on and concentric with the discs of the stubs 22, 22', after which the rod 25 may be inserted through the apertures of all of the said discs with the head of the rod resting on the disc of the stub 16, thereby connecting the two units of each hinge into a complete assembly, as in Fig. 1, and thereby supporting the gate in swinging position upon the post.

It will now be seen that by loosening the set-screws 8—8, 8'—8', and the nuts 17—17 and 17'—17', that the stubs 16, 16', may be adjusted laterally forward or rearward or to the right or the left, after which said set-screws and nuts may again be tightened; also that by loosening the set-screws 24 the stubs 22, 22', may be moved up or down, or may be rotated in their nuts 23, 23', whereby the stubs 22, 22', may be adjusted longitudinally to the right or the left, after which said set-screws 24 may be tightened. All of said adjustments will enable one to change the position of the gate with relation to the post, and by which one is enabled to at any time slightly raise or lower the outer end of the gate either to level it or to align it with its latch, or with another gate; and to permit the top or the bottom of the gate to be adjusted forward or backward for various reasons, such, for instance as to cause the gate to raise over some obstruction as it is swung open or closed.

I desire that it be understood that va-

rious changes may be made in the several details of construction and the shape and the arrangement of the several parts, without departing from the spirit of the invention and without sacrificing anything therein which is new and useful, and which involves invention.

Having now fully shown the preferred means for carrying out the principles of my invention, what I claim, and desire to secure by Letters Patent of the United States, is—

1. In combination with a concrete post, box-like hinge members imbedded in the post and projecting slightly from the face thereof, a hinge stub carried by each of said hinge members, and means whereby said stubs may be adjusted longitudinally and vertically.

2. In combination with a gate and a concrete post, box-like hinge members imbedded in the post and projecting slightly from the face thereof, a hinge stub carried by each hinge member, means whereby said stubs may be adjusted longitudinally and vertically, hinge members carried by the gate and including a hinge stub, and means for adjusting the last named hinge stub horizontally to various angles and also longitudinally thereof.

3. Adjustable gate hinges, comprising a gate assembly and a post assembly, the post assembly comprising a boxing secured in the post, a nut located loosely in the boxing, a stub having its shank portion threaded in

said nut and extending out through the projecting end of the boxing with a disc forming the outer portion of said stub, means for securing the stub rigid with the boxing but permitting it to be adjusted vertically; the gate assembly carried by the gate and including a stub with a disc forming one end thereof, means for securing the gate stub in rigid position and providing the means whereby the gate stub may be adjusted horizontally at various angles, and means for rotatably connecting the two discs together.

4. Adjustable gate hinges, comprising two gate assemblies and two post assemblies, each of the post assemblies comprising a boxing imbedded in the post with one end protruding therefrom with a vertical slot formed in the protruding end, a nut located in each boxing, a stub disposed through said slot with a disc located on the portion outside said slot and with the inner end of the stub threaded into said nut, means for securing said stubs at any elevation within the limits of said slot; each of the gate assemblies including a stub having a disc on its outer end and adapted to be moved laterally, means for securing the gate stubs at various positions within the limits of its movements; and a rod extending through all of the stubs of both the post and the gate assemblies and forming a pivotal connection therefor.

JAMES M. DODDRIDGE.
